UNITED STATES PATENT OFFICE.

ALBERT R. PRITCHARD, OF NEW YORK, N. Y.

CONVERTIBLE FREIGHT-CAR.

1,283,890.

Specification of Letters Patent.

Patented Nov. 5, 1918.

Application filed December 31, 1917. Serial No. 209,624.

To all whom it may concern:

Be it known that I, ALBERT R. PRITCHARD, a citizen of the United States, residing in the borough of Manhattan, city, county, and State of New York, have made certain new and useful Improvements in Convertible Freight-Cars, of which the following is a specification.

My invention relates to freight cars and 10 has as its principal object the provision of a car so designed that it may be used either as a box car or as a coal car.

The second object of my invention is to provide a car which may be used either as a 15 box car, a coal car or a flat car.

Further objects of my invention will appear from the following specification and claims.

As is well known, it is impracticable to 20 ship certain classes of freight in a box car, while it is also impracticable to ship other classes of freight in a coal car, and it is impracticable to ship certain classes of freight in either the box car or the coal car, a flat 25 car being necessary. The consequence is that the railroad companies find it necessary to keep on hand more cars of each type than their average business calls for. Moreover, it is necessary to move a large tonnage 30 of empty cars owing to the fact that the cars of a certain type are at certain points when the need for them arises, and it is not possible to use cars of other types. It is evident from this that the non-convertibility of the 35 cars now in use causes unnecessary expense not only from the additional investment in cars and sidings, but also in the additional operation. I have shown in the accompanying drawings forming part of this application, two practical forms of cars embodying 40 my invention.

In said drawings,

Figure 1 is an elevational view partly broken away of a car embodying my invention 45 in one form thereof.

Fig. 2 is an elevational view looking in the same direction as in Fig. 1, and showing the same car arranged as for carrying coal.

Fig. 3 is a cross section taken on the line 50 3—3 of Fig. 1 looking in the direction of the arrows.

Fig. 3^a is a sectional view on the line 33—33 looking in the direction of the arrows.

Fig. 4 is a separated sectional view show-

ing the manner of assembling and separating certain of the parts appearing in Fig. 3.

Fig. 5 is a top plan view of a portion of a car as arranged in Fig. 2.

Fig. 6 is a detail sectional view on the line 60 6—6 of Fig. 2.

Fig. 7 is a detail sectional view on the line 7—7 of Fig. 1.

Fig. 8 is a detail view in perspective showing the lower portion of one of the side 65 posts of the doorway and its relation to the surrounding parts.

Fig. 9 is a detail sectional view showing a modified arrangement for attaching the 70 upper side panels to the lower side panels.

Fig. 10 is a detail separated view showing the manner of assembling the ridge-pole, with the end of the car.

Fig. 11 is a perspective view showing the 75 under side of a portion of one of the roof members.

Fig. 12 is a perspective view of the ridge-pole.

Fig. 13 is a perspective view of a portion 80 of one of the upper detachable side members.

Fig. 14 is a perspective view of one of the upper detachable end members.

Fig. 15 is a perspective view showing the under portion of the running board.

Fig. 16 is an elevational view partly separated similar to Fig. 2, of a second form of 85 car embodying my invention.

Fig. 17 is a detail cross section taken on the line a—a of Fig. 16.

Fig. 18 is a detail sectional view taken on 90 the line b—b of Fig. 16.

Fig. 19 is a detail sectional view taken on the line d—d of Fig. 16, looking in the direction of the arrows.

Fig. 20 is a detail sectional view taken on 95 the line c—c of Fig. 16.

Throughout the separate views the same part is designated by the same reference character.

Referring more particularly to the drawings, 1 is the center sill of a car running longitudinally thereof, the part 1 being of any standard or preferred construction. The ordinary standard draft and running gear are preferably associated with the sill 1 100 in the usual manner. Supported from the sill 1 by suitable boasters 2 are two side sills, such as 3, which are shown as slightly shorter than the center sill, but slightly longer than the dimensions of the car over 105 110

the upright end members. Supported by the side sills 3 are composite lower side members or panels, such as 4, comprising vertical T-bars such as 5, the lower ends of which overlap the side sills 3, and which are fastened thereto permanently as by rivets, as shown in Fig. 3, or by a detachable connection as desired. At the upper ends of the T-members 5 are horizontal Z-members, such as 6, of special cross section, arranged on the inside of the members 5, and within the Z-members 6 are plates such as 7, the members 5, 6 and 7 being riveted together to form the panels 4. The two side panels 4 are spaced apart 10 on both sides of the car to provide a doorway, as is usual in box car construction, and the edge of the panel at the doorway is formed with a vertical spacing plate, such as 8, of the same thickness as the lower portion 15 of the Z-bar 6, a channel iron, such as 9, on the outside of said plate, and a recessed or rabbeted plate, such as 10, on the inside of the plate 7, the members 9 and 10 projecting into the door space from the members 7 and 8 and forming a vertical recess 20 or slot, the purpose of which will appear herein below.

When the car is to be used as a box car, the sides must be built up above the panels 30 4 and a roof structure, as well as doors, must be provided. For this purpose I provide upper side members or panels, such as 11, which are designed to rest upon the panels 4 and which comprise a lower horizontal 35 channel-bar, such as 12, the recess 13 in the lower edge of which is designed to fit over the upwardly extending flange of the Z-bar 6. The members 12 support vertical plates such as 14, plates 14 being preferably corrugated to combine lightness with strength, the lower edges of plates 14 being held between complementary corrugated surfaces of clamping plates, such as 15 and 16, which are riveted in turn to the members 12. The 40 upper edges of the plates 14 are also clamped between plates, such as 17 and 18, which are corrugated to fit the plates 14, members 14, 17 and 18 being held together by countersunk rivets. In order to hold the panels 50 11 securely on the Z-members 6 of the panels 4, I provide set screws, such as 19, the ends of which are designed to engage in recesses, such as 20, in the members 6.

Supported in part on the panels 11 are 55 roof-members or panels such as 21, which comprise channel-bars or members 22, running along the outer edges of the panels 21, and having a slot or recess in their lower edges adapted to receive the plates 17 and 18 60 at the upper edges of the panels 11. The panels 21 are only half the width of the car and at their inner edges comprise angle-irons, such as 23, one web of which extends vertically downward and is adapted to engage 65 in a slot provided in the ridge-pole.

The ridge-pole is shown at 24 and comprises a central vertical web or plate 25, on each side of which are riveted Z-bars, such as 26, the upper flanges of the Z-bars being offset from the plate 25 to provide sockets or recesses for receiving the angle-irons 23. The panels 21 are secured to the panels 11 and to the ridge-pole 24 by means of set screws in a way similar to the action between panels 4 and 11. The plates of the panels 21 70 connecting the members 22 and 23 are preferably formed largely of corrugated metal, riveted to the members 22 and 23.

The central web or plate 25 of the ridge-pole is made sufficiently wide to project 80 above the roof panels 21, so that a running board 27 may be conveniently attached thereto, said member appearing in detail in Fig. 15 and comprising a pair of downwardly projecting flanges such as 28, which run one on each side of the longitudinal center line of the running board, forming a slot for the reception of the upper edge of the member 25. The running board 27 is provided with hand holes, such as 29, through 90 which bolts may be inserted into conveniently provided holes in the flanges 28 and plate 25, to hold the running board in place.

The lower end panels, such as 30 (see Fig. 3) are constructed similarly to the side panels 4. Mounted on the panels 30 are upper end panels such as 31, preferably formed largely of corrugated metal, the upper and lower edges of the panels 31 being constructed similar to the corresponding parts of 100 panel 11. The vertical side edges of panels 31, however, are provided with angle-irons such as 32, shown in Figs. 7 and 14, which provide recesses for receiving the vertical edges of the panels 11, the end members, such as 33, of the panels 11 having bolt holes therein corresponding to holes in members 32, whereby the parts may be secured together. The connection between the roof-members 21 and the end panels 31 is similar to that between the panels 21 and 11, as appears clearly from Figs. 11 and 14. The ridge-pole is provided with notches, such as 34, at the ends of the center plate 25, the notches 34 receiving the upper edges of 115 the panels 31 to prevent longitudinal movement of the ridge-pole, and the panels 31 also are provided with notches, such as 35, for receiving the center plate 25 to prevent lateral movement of the ridge-pole.

I may provide pins, such as 36, at the upper edges of the panels 11 for entering sockets, not shown, in the channel members 22 of the panels 21 to position panels 11 and 21 with respect to each other and further hold 125 the same in place.

Referring more particularly to Figs. 16 to 20 inclusive, I have therein illustrated a further extension of my idea as embodied in Figs. 1 to 15 inclusive, in that Figs. 16 to 130

20 inclusive show an arrangement wherein the lower panels also may be removed to produce a flat car. As shown in Fig. 16, the side sills 3' have plates, such as 37 and 38, 5 riveted thereto forming sockets for the reception of the lower ends of the vertical members such as 5' and 9' of the panels 4'. The end panels, such as 30' are supported in a similar manner to the panels 4', and for 10 further security I may attach angle-irons such as 39 to the lower edges of the panels 4' and 30', and bolt the members 39 to the side sills 3' as indicated in Figs. 19 and 17. A hand hole, such as 40, may be provided in 15 the lower floor of the car for this purpose. The end member 30' is also further modified, in that it is provided with angle-irons, such as 41, at its vertical edges which may be bolted to the adjacent edges of the panels 4'. In other particulars the arrangement shown in Figs. 16 to 20 is identical 20 with that shown in Figs. 1 to 15 inclusive.

The door structure for each of the embodiments of my invention is illustrated in 25 Figs. 1 and 3^a, where 45 indicates a door member, the upper edge of which carries wheels, such as 46, which run on the in-turned flanges of members 47 and 48. The upper edges of the members 47 and 48 are 30 spaced from the members 22 by means of blocks, such as 49, and are supported by bars such as 51, which are arranged in the panels of the members 9 when the door is in use, 35 projecting above the members 9 to the level of the roof member 22 and being fastened to members 22, 47 and 48 by bolts such as 50. The lower ends of the bars 51 are fastened to the side sills 3 by bolts, such as 52, the bolts 52 also securing in place a Z-iron 40 53, the upwardly extending flange of which protects the lower edges of the door. It will be evident that the doors and supporting structures therefore can be easily removed by taking out the bolts 50 and 52. It 45 will be seen that bars 51 not only assist in supporting the door structure, but also reinforce the framework of the car around the door-way.

When it is desired to change one of my 50 improved cars from a box car type to a coal car type, the roof structure and the upper side and end panels, together with the doors, are removed and one of the upper side panels is inverted and placed across the door-way, 55 the edges of panel 11 being inserted into the slot formed by members 9 and 10, to which reference was previously made. The parts not in use may be stored in the space 41 between the upper floor plates 42 and the lower floor plates 43, plates 42 and 43 being 60 supported on the side sills. Access to the space 41 may be obtained by raising certain of the plates 42, or by removing an end cap, such as 44, which overlies the ends of the 65 side sills 3.

It will be seen that I have provided means whereby a given car may be used either as a box car or as a coal car in one instance, or either as a box car, coal car or flat car in the other instance. Moreover, the detachable parts can be conveniently stored and transported with the car when not in use, so that they will be immediately available when it is desired to again change the type of car. 70

It will be understood that I have shown the preferred embodiment of my invention as now known to me, but I do not wish to be limited to the arrangement or form of the parts herein shown and described. 75

Having thus described my invention, I claim:

1. A freight car having a detachable roof and including means forming a storage space for said roof when detached beneath 80 the floor of said car.

2. A freight car comprising a detachable roof, detachable side members for supporting said roof, and means providing a storage space for said roof and side members 90 when detached beneath the floor of said car.

3. A convertible freight car adapted for use as a box car or coal car, comprising detachable upper side members constructed and arranged when the car is used as a box 95 car to provide a doorway, and detachable door members for closing said doorway when desired, one of said members being proportioned to form a fixed closure for the lower portion of said door space when the 100 car is used as a coal car.

4. A convertible freight car adapted for use as a box car or coal car, comprising a floor, detachable upper side members, a detachable roof structure, and means forming 105 a storage space for said roof and members beneath the floor of the car.

5. A convertible freight car adapted for use as a box car or coal car, comprising detachable upper side members constructed 110 and arranged when the car is used as a box car to provide a doorway, and detachable door members for closing said doorway when desired, one of said upper side members being proportioned to form a fixed closure for the upper portion of said door space 115 when the car is used as a coal car.

6. A convertible freight car comprising a floor, walls divided horizontally so that the lower part of said walls is removable from 120 said floor and the upper part of said walls is removable from the lower part, a removable roof, and means forming a storage space for said walls and roof beneath said floor.

7. A convertible freight car comprising a 125 floor, walls composed of a plurality of members and divided horizontally so that the lower members of said walls are removable from said floor and the upper members of said walls are removable from said lower 130

members, a removable roof, and means forming a storage space for said wall members and said roof beneath said floor.

8. A convertible freight car comprising a floor, walls composed of a plurality of members and divided horizontally so that the lower members of said walls are removable from said floor and the upper members of said walls are removable from said lower

members, said walls being so constructed ¹⁰ that when the car is used as a box car a doorway is provided, and removable door members for closing said doorway when desired, one of said upper wall members being proportioned to form a fixed closure for said ¹⁵ doorway when the car is used as a coal car.

ALBERT R. PRITCHARD.
